(57) **CLAIM**

The ornamental design for a wrist watch, as shown and described.

DESCRIPTION

This application relates to subject matter contained in disclosure document number 478629, filed in the United States Patent & Trademark Office on Aug. 4, 2000.

FIG. 1 is a perspective view of a wrist watch.

FIG. 2 is a front elevational view thereof.

FIG. 3 is a rear elevational view thereof.

FIG. 4 is a right side elevational view thereof, the left side elevational view being a mirror image of the right side view.

FIG. 5 is a bottom plan view of the wrist watch; and,

FIG. 6 is a top plan view thereof.
